S. BERG

MACHINE FOR SIZING TUBING

Filed July 28, 1922

By

SIMON BERG
Stuart C Barnes Attorney

UNITED STATES PATENT OFFICE.

SIMON BERG, OF DETROIT, MICHIGAN, ASSIGNOR TO MICHIGAN STEEL TUBE PRODUCTS COMPANY, OF DETROIT, MICHIGAN, A CORPORATION OF MICHIGAN.

MACHINE FOR SIZING TUBING.

Application filed July 28, 1922. Serial No. 578,059.

To all whom it may concern:

Be it known that I, SIMON BERG, citizen of the United States, residing at Detroit, in the county of Wayne and State of Michigan, have invented certain new and useful Improvements in Machines for Sizing Tubing, of which the following is a specification.

This invention relates to a machine for swedging or sizing tube. The object of the machine is to eliminate any irregularities in formation and to accurately size the tubing to the desired diameter.

The improvement herinafter claimed resides in the cage construction. The cage is made from a single casting and a retaining plate and so designed that it will take the shocks of the hammer blocks and hammer block rolls without untimely wear. A cage of this construction will last very much longer than the ordinary cage construction.

In the drawings,—

Fig. 1 is a vertical cross section of a swaging machine showing the rotor and roller cage in elevation.

Fig. 2 is a longitudinal section of the same, taken on the line 2—2 of Fig. 1.

Fig. 3 is a rear view of the cap plate that is bolted to the roller cage.

Fig. 4 is a side elevation of the rotor.

Fig. 5 is a side elevation of the cage casting.

a designates the housing of the machine in which is contained a cage *b*. This cage is made up of a ring *c* which is a single casting and the cap or end plate *d*. This casting is formed with a plurality of roll sockets *e* having rounded ends *f*. The rolls *g* fit into the open ends of the roll sockets and protrude through the ring at either side as shown at *j* and *i* in Fig. 1.

The cap plate *d* is secured to the end of the cage ring by the cap screws *k*, dowel pins *m* fit into the dowel pin holes. This plate has machined thereon inwardly projecting bosses *n* that fit into the roll socket and serve to locate and hold the ring firmly to the end of the casting.

The rotor *p* is provided with a cross slot *q* in which slide the hammer blocks *r* and the two dies *s*. When the rotor is revolved and a tube *t* lies between the dies, the hammer blocks *i* are caused to reciprocate due to striking the rolls *g*. This reciprocates the

dies and forces them upon the tube thereby hammering the tube down to size and accurate configuration.

Each of the rolls *g* is provided with a rounded and tapered inner end which fits into the rounded end of the roll socket. The ends of the roll sockets are somewhat spaced from the end of the casting so as to form a heavy web at this place so as to take the thrust and wear. The idea of making this end of the cage a heavy solid casting in place of a plate, very materially adds to the strength of the cage, resists wear and breakage much longer than a cage constructed in the ordinary way with a simple plate at this end of the cage. Furthermore it permits the use of a spherical end socket and a roller with a rounded end. This construction is better adapted to take the thrust of the roller without undue wear.

What I claim is:

1. In a machine for the purpose specified, the combination of a cage in the form of a ring casting solid at one end and provided with a plurality of open-ended, open-sided roll sockets, rolls contained in said sockets and a plate provided with inwardly projecting bosses for fitting into the ends of the roll sockets and removably secured to the open end of the ring casting.

2. In a machine for the purpose specified, a cage comprising a solid end casting provided with open-sided, open-ended roll sockets having at their inner ends a rounded conformation, hammer block rolls rotatably supported in said sockets and provided at their inner end with rounded ends for engaging the rounded ends of the roll sockets, and means for retaining the rollers at the open ends in the ring casting.

3. In a machine for the purpose specified, a cage comprising a solid end ring provided with open-ended, open-sided roll sockets having at their inner ends substantially spherical configuration, hammer block rolls provided with rounded inner ends supported in said roll sockets and a retaining plate removably secured to the open end of the ring casting and provided with inwardly projecting bosses projecting into the inner ends of the said sockets.

In testimony whereof I affix my signature.
SIMON BERG.
